ELECTRIC SWITCH CONTACT ASSEMBLY

Harold E. Schleicher, West Hartford, Conn., assignor to The Arrow-Hart & Hegeman Electric Company, Hartford, Conn., a corporation of Connecticut

Application December 1, 1950, Serial No. 198,680

7 Claims. (Cl. 200—166)

1

This invention relates to an improved contact assembly for an electric switch and is particularly useful in electro-magnetically operated switches but its use is not limited thereto.

In switches wherein the pair of fixed contacts are adapted to be connected by a movable bridging contact, the condition of the contacts is usually normally-closed or normally-open. Often it is desired to change the relation from normally-closed to normally-open and vice-versa. This need may occur after the switch has been assembled and perhaps has been sold and put in service; or it may occur before assembly by reason of a customer's order specifying certain contact relationships.

Various means have heretofore been provided for reversing both the fixed contacts and the movable bridging contact requiring at least three manual manipulations, since each of the two fixed contacts would have to be reversed or interchanged and the movable contact would also have to be reversed.

It is an object of the present invention to provide a contact assembly wherein only the fixed contacts need be reversed or interchanged in order to change the switch from a normally-open to a normally-closed condition or vice-versa.

Another object of the invention is to provide an assembly to accomplish the foregoing objective wherein the contacts are interchangeable in order to reduce the cost of tools and to lower manufacturing costs and inventories.

Another object is to provide a contact assembly of the foregoing type in which the parts may be economically manufactured and assembled or reassembled, without sacrificing quality or reliability of operation.

Other objects and advantages of the invention will become apparent as it is described in connection with the accompanying drawing.

In the drawing:

Fig. 1 is a plan view of two poles of an electro-magnetic switch embodying the invention.

Fig. 2 is an end elevation view of the structure of Fig. 1, partly in section along line 2—2 of Fig. 1.

Fig. 3 is an enlarged section view of the movable contact member and mounting, taken along line 3—3 of Fig. 1.

Fig. 4 is a section view similar to Fig. 3 of another form of movable contact mounting.

Referring to the drawing, the invention is described for convenience as applied to an electro-magnetically operated switch but it will be under-

2

stood that the invention is not limited to such use since any other operating means might be employed as well. A conventional electromagnetic operating means is mounted upon the base plate 10 and includes a pivoted movable armature member 12 in a metal frame member 14. The armature is pivotally mounted about a pin 16 in the frame member 14 and has an arm 18 attached thereto which in turn is pivotally mounted at its end by a pin 20 to a movable contact carrier 22. Upon the movable contact carrier are mounted upper and lower insulating bars 24 and 26 which extend transversely across the switch. The bar 26 lies on top of the bar 24 and is of similar shape and dimension. The two bars may be secured together upon the supporting member 22 by bolts 28 spaced therealong.

The contact supporting bars 24 and 26 move within a recess shaped and provided for that purpose transversely in a base member 30 which may be made of molded insulation or other suitable insulating material.

Mounted at opposite sides of the insulating base member 30 on the top face thereof are fixed contact members 32 and 34. These contacts may be stamped from sheet metal to provide each with a terminal or mounting portion such as 32t and 34t lying upon the top surface of the insulating base 30 and secured thereon by screw bolts 33. Each may also have a contact portion 32c and 34c offset from the terminal portion in a downward direction as illustrated in full lines in Fig. 2. On the upper surface of these contact portions, conventional contact buttons 32b and 34b of good conducting material may be provided for engagement with similar contact buttons on a movable bridging contact member 40 described below.

The bridging contact 40 may be stamped from thin resilient sheet metal such as Phosphor bronze, copper or other highly conductive resilient material in the form of a strip. The strip is mounted transversely between the upper and lower insulating bars 24 and 26 on a contact carrier in the following manner. The adjacent surfaces of the insulating bars 24 and 26 are recessed transversely at spaced points to provide spaced passageways 42 through which a series of bridging contacts pass, one for each set of stationary contacts like 32, 34. Pressing against the upper and lower surfaces respectively of the bridging contact at its central portion are opposite identical cylindrical sleeve members 44 and 45. These sleeve members are adapted to

slide within cylindrical bores 46 and 47 in the insulating bars 24 and 26. Seated against the bottom of each bore is a coiled compression spring 48 and 49, whose opposite end presses against the peripheral edge of the sleeve member which is within the bore, thus urging the members 44, 45 oppositely against the opposite sides of the bridging contact.

Necks 50 and 51 of reduced diameter are formed on the inner ends of each of the sleeves 44 and 45 around the central portion of identical anchor members 52, 53. These central portions are substantially cylindrical and are hollow to receive the opposite ends of a round guide rod 55 which is coaxial with the sleeve members 44 and 45 and passes through a hole in the middle of the bridging contact 40. The inner ends 54 of the anchor members are reduced in diameter and screw threaded to fit within bores or cylindrical recesses coaxial with and in the bottoms of the larger bores 46, 47 in the insulating members 24 and 26. In this way the anchor members 52 and 53 are frictionally held in place upon the insulating bars 26 and 24 respectively. In order to prevent the springs 48 and 49 from pressing the sleeve members 44 and 45 off of the anchor members 52 and 53 during assembly, a flange 56 is provided upon the proximate ends of each of the anchor members 52 and 53. These flanges lying within the sleeve members adjacent their necks 50, 51 prevent the sleeves from moving off the anchor members while the two bars 24, 26 are being joined.

From the foregoing, it may be observed that the anchor members supply the means to mount the sleeve members upon the insulating bars 24 and 26 and the springs 48 and 49 press the sleeve members toward each other and against the opposite surfaces of the bridging contact member 40. In this way, the bridging contact member 40 is supported floatingly by the springs 48, 49. When the contact buttons on its ends engage the contact buttons on the fixed contact members 32 and 34 the bridging contact is permitted to move within the recess 42 between the insulating bars 24 and 26 to adjust itself and to maintain contact engagement and pressure.

Upon energization of the electromagnet, the armature 12 through the arm 18 and carrier member 22 will cause upward movement of the contact carrier bars 24 and 26 and will move the bridging contact away from the fixed contacts after the bridging contact has come to its mid-position as the action of the compression springs 48 and 49 equalizes. During such movement, the bridging contact is guided by the guide rod 55 which also acts to hold the movable contact against movement endwise while permitting tilting movement due to the loose fit of the guide rod in the hole of the contact.

Alongside of the fixed contacts 32 and 34 are or may be mounted a second set of fixed contacts 62 and 64 of identical form to the fixed contacts 32 and 34. These contacts 62 and 64 however are mounted (as shown in dotted lines in Figs. 2 and also in plan in Fig. 1) so that their offset portions 62b, 64b extend upwardly or in other words are located in a plane above the terminal portions 62t and 64t which rest on the upper surface of the insulating base 30 in the same plane as 32t and 34t. Extending between the fixed contacts 62 and 64 is a bridging contact 41 exactly like bridging contact 40 and mounted in the same as the bridging contact 40; but the contact buttons on the upper surface engage the

fixed contacts 62, 64 whereas the buttons on the lower surface engage contacts 32, 34. It will be observed however that due to the way these fixed contacts 62 and 64 are mounted, the bridging contact 41 will be normally disengaged from them when the bridging contact 40 is engaged with the contacts 32 and 34. It will now be apparent that if it should be desired to have the fixed contacts 62 and 64 normally engaged by the bridging contact 41, it is only necessary to invert those contacts and reverse their positions, i. e. putting the contact 62 in place of the contact 64 while turning it up side down and vice-versa. And the same applies to contacts 32 and 34 if it should be desired to have them normally disengaged from the bridging contact 40. The floating mounting of the bridging contact enables proper contact engagement and pressure regardless whether the fixed contacts are mounted for normally-open or normally-closed conditions.

In the drawing of Fig. 1, the fixed contacts are shown as having their contact portions angularly displaced with relation to the terminal portions but this is not essential. The terminal contact portions could be in alignment if desired.

In Fig. 4 wherein like reference numerals indicate like parts in Fig. 3, I have illustrated another form of mounting for the movable contact member. In this form the bars 24 and 26 forming the movable contact carrier have bores 46 and 47 and a recess 42 at their adjacent surfaces as before. In this form however the movable contact guide rod 155 has its ends received within borings similar to those which received the end portions of the anchor members in the previously described form. The mid-portion of the guide rod 155 is enlarged as at 156 and the hole in the bridging contact 140 is likewise enlarged to accommodate the enlarged portion 156. Sleeve members 144, 145 have flanges 157, 158 whose proximate surfaces press against opposite sides of the bridging contacts 140, while the opposite sides of the flanges form seats for the springs 48 and 49.

In each of the forms of mounting for the bridging contact member if it should happen that the movement of the movable contact supporting bars 24 and 26 exceeds the limit of movement permitted by the recess 42, the resilience of the contacts themselves will permit some additional movement. Thus, not only do the springs 48 and 49 permit the bridging contact to accommodate itself in engaged position to the fixed contacts but also the resilience of the bridging contacts will permit some overtravel.

From the foregoing, it may be observed that I have provided a contact assembly and mounting wherein normally engaged fixed and bridging contacts may be readily converted to normally disengaged condition by only transposing and inverting the fixed contact on one side with the fixed contact on the other side of any set. Moreover, the fixed contacts of any set are interchangeable with any other set as are also the bridging contacts.

Many modifications within the scope of the invention will occur to those skilled in the art. Therefore I do not limit the invention to the exact form and detail as illustrated and described.

What is claimed is:

1. In an electric switch, a bridging contact movable to engage and disengage fixed contacts, a movable carrier for said bridging contact comprising cooperating insulating members beyond

which said bridging contact extends, a passage between said members at their cooperating faces in which said bridging contact is located and movable, sleeve members on opposite sides of said bridging contact, and spring means between each insulating member and sleeve member pressing said sleeve members against said bridging contact on opposite sides thereof whereby said contact is floatingly mounted, and a guide member running between said insulating members and through said bridging contact guiding the movement of said bridging contact.

2. In an electric switch as claimed in claim 1, means engaging said sleeve members to movably secure them to their respective insulating members against the stress of said spring means during assembly.

3. An electric switch as claimed in claim 1, anchor members attached to each insulating member each having a flanged portion holding a sleeve member movably on its insulating member against the stress of said spring means during assembly.

4. An electric switch as claimed in claim 1, wherein the guide member comprises a rod having its opposite ends in said insulating members, and an enlarged mid-portion within and guiding the movement of said sleeve members and said movable contact.

5. An electric switch as claimed in claim 4 having means to limit the movement of each sleeve member by the spring means which engages it, whereby that spring means becomes ineffective while the opposite spring means becomes compressed during contact engagement.

6. In an electric switch as claimed in claim 1, means engaging said sleeve members to movably secure them to their respective insulating members against the stress of said spring means, and 5 means to limit the movement of each sleeve member by the spring means which engages it, whereby that spring means becomes ineffective while the opposite spring means becomes compressed during contact engagement.

10 7. An electric switch as claimed in claim 1, anchor members attached to each insulating member each having a flanged portion holding a sleeve member movable on its insulating member against the stress of said spring means, and 15 means to limit the movement of each sleeve member by the spring means which engages it, whereby that spring means becomes ineffective while the opposite spring means becomes compressed during contact engagement.

HAROLD E. SCHLEICHER.
